Application September 30, 1942. Serial No. 460,312

8 Claims. (Cl. 24—261)

This invention relates to the gluing of the overlapping flaps of fibreboard cartons, and particularly to a clamping device which is adapted to hold in intimate contact with one another the previously glue-coated overlapping flaps of such a fibreboard carton while the glue dries.

The gluing of carton flaps and particularly where the contents do not completely fill the carton and support the inner flaps, has heretofore been difficult to perform effectively because the inner flaps have tended to rotate inwardly on their score lines as hinges and thus to prevent contact between glue-coated surfaces of the overlapping flaps. It has been a common practice to apply pressure upon the upper surface of the carton to press the outer flaps into contact with the inner flaps while the glue is drying. However, where the contents do not entirely fill the carton and fail to provide internal support for the inner flaps, pressure applied on upper surface of the outer flaps has the effect of causing the inner flaps to rotate inwardly on their score lines into the unfilled space within the carton with the result that adequate contact between glued surfaces is prevented and little or no adhesion is obtained. It has also been a common practice to seal cartons by applying an adhesive tape to the seams formed by the edges of the outer flaps. However, this method of sealing does not provide the necessary rigidity in those faces of the carton formed by the overlapping flaps and the use of adhesive or other bond between outer and inner flaps is necessary to provide the rigidity required for protection of contents. Glue is the cheapest and simplest means of obtaining the required bond between the overlapping flaps. However, the attainment of a satisfactory glue bond requires that inner flaps be held in intimate contact with outer flaps while the glue dries. In sealing cartons exclusively with glue no means now exists to effectively maintain such contact between flaps when the inner flaps are not supported by contents of the carton.

The present invention seeks to enable the effective sealing of cartons exclusively with glue by providing a means of maintaining intimate contact between inner and outer flaps while the glue dries and seeks to provide a carton which when glued utilizes the lamination of the glued surfaces to materially increase the resistance of the carton to external stress and pressure and thus better protect contents of the carton.

It is an object of the present invention to facilitate the attainment of a strong bond between the overlapping flaps of cartons whose contents do

not firmly support the inner flaps against pressure on the outer flaps.

It is another object of the invention to facilitate the gluing of the overlapping flaps of the carton together with such an area of adhesion that the use of adhesive tape may be eliminated and that the carton will provide protection to its contents superior to that heretofore provided.

10 A further object of the invention is to provide a resilient clasp which is adapted because of its novel construction to engage simultaneously the inner flaps and the overlapping outer flaps of a carton and maintain them in intimate contact with one another over an extensive area so that glue previously applied to surfaces of such flaps will cause them to firmly adhere to one another over such extensive area.

Another object of the invention is to provide a 20 clasp for holding in intimate contact the previously glue-coated inner flaps and the overlapping outer flaps of the carton while the glue dries, which clasp is constructed so as to be readily insertable between the adjacent edges of the 25 outer flaps to hold the inner flap in contact with the outer flaps, and which clasp may be readily removed from the carton for subsequent use after the glue has dried.

Another object of the invention is to provide 30 a clasp which may be inserted between the closely adjacent edges of outer flaps of the carton into the space within the carton and adapted to lift into contact with the outer flaps an inner flap which may have rotated on its score line to a 35 position below the plane of contact with the outer flaps.

The above and other novel features of the invention will appear more fully hereinafter from the following detailed description when taken in 40 conjunction with the accompanying drawings. It is expressly understood, however, that the drawings are employed for purposes of illustration only and is not designed as a definition of the limits of the invention, reference being had for this 45 purpose to the appended claims.

In the drawings wherein like reference numerals indicate like parts,

Figure 1 illustrates a carton in perspective view with the flaps unglued, illustrating roughly the 50 manner of applying to the flaps the clasp which constitutes the object of the invention:

Figure 2 illustrates the manner in which the carton of Fig. 1 is operated upon by insertion of the clasp and orientation of the clasp to the plane 55 of the flaps of the carton, so as to draw the inner

and outer flaps into engagement with one another;

Figure 3 illustrates the clasps slid into their ultimate position so that their points of contact with the flaps are in resilient engagement with the flaps of the carton to resiliently maintain the flaps in intimate contact with one another over an extensive area;

Figure 4 is a perspective view illustrating the general shape of the clasp;

Figure 5 is a side view of the clasp;

Figure 6 is a front view of the clasp; and

Figure 7 is a top plan view of the clasp.

Referring to Fig. 1 there will be seen the usual fibreboard carton generally indicated by the reference numeral 10, which carton has on its top a pair of outer side flaps 12 and 14 and inner end flaps 16 and 18. The pair of outer flaps 12 and 14 in conjunction with the pair of inner flaps 16 and 18 are so arranged as to substantially close the top of the carton.

In such cartons, when so packed that the contents do not tightly fill the carton, the inner flaps 16 and 18 are unsupported by any inside resistance such as would exist in a tightly filled carton. For this reason there is nothing to hold the inner flaps in contact with the outer flaps, and if the inner flaps should rotate inwardly on their score lines within the carton and away from the plane of the outer flaps, it becomes difficult to obtain sufficiently intimate contact between glued surfaces of the outer flaps and inner flaps to produce a strong adhesive bond when glue has dried. On the other hand, as has been pointed out, if the outer flaps are taped together by adhesive tape extending parallel with edges of the outer flap, there is still no assurance that glued surfaces of the inner and outer flaps will be held in intimate contact over a sufficient area to produce a satisfactory bond.

In order to assure that the inner flaps and the outer flaps are held in intimate contact with one another over a considerable area, the present invention contemplates the use of a clasp constructed substantially as is illustrated in Figs. 4 through 7. As illustrated the clasp consists of a piece of heavy stiff resilient wire, the same being bent so as to provide an elongated tongue portion 20 and transverse bearing portion 22 joined to the tongue portion by an angle section 24 and a ring handle portion 26 extending from one end of the transverse bearing portion 22. The tongue portion 20 at its extreme end may be balled or rounded by bending over a short end thereof as at 28 and at its other end is joined through the short end 30 to the angle section 24, which in turn is joined to one end 32 of the transverse bearing portion 22. At the other end of the transverse bearing portion 22, namely at 34, the wire is provided with a short bend which thereafter flows into the ring 26 which forms a handle. As illustrated in Fig. 5 the handle portion extends upwardly and away from the tongue portion and transverse portion inclines rearwardly away from the balled end 28 of the tongue. The handle is so inclined in order to facilitate application and removal.

In employing the clasp for the purpose heretofore described, reference will be had to Figs. 1 to 3, inclusive, for a description. The adjoining surfaces of the inner or outer flaps of the carton are suitably coated with glue or any other suitable adhesive. The flaps are then arranged substantially in the position shown in Fig. 1 and the ball point 28 of the tongue 20 is inserted between

the closely adjacent edges 36 and 40 of the outer flaps 12 and 14 near the middle of the top. The tongue is then manipulated within the outer flaps to engage the inner flap, for example 16, and to lift the inner flap into contact with the outer flaps 12 and 14. The clasp is then rotated about an axis substantially coincident with the transverse bearing portion 22 to bring the tongue 20 into a position substantially parallel with the plane 10 of the outer flaps 12 and 14 and to elevate the inner flap 16 into engagement with the outer flaps 12 and 14 as illustrated in Fig. 2. Thereafter as illustrated in Fig. 3 the clasp is slid along the narrow slot formed by the edges 36 and 40 15 towards the end of the carton in order to bring the bearing points 32 and 34 toward a central portion of the overlapping areas of the flaps 12 and 14 and 16, and at the same time to cause substantially the entire length of the tongue of 20 the clasp to bear against the under side of the inner flap. The bearing points 32 and 34 bear such a relation to the upper surface of the tongue as to force the outer flaps into intimate contact with the inner flap over a considerable area and 25 with a pressure substantially equal to that required to assure a satisfactory engagement during the time the glue is drying. Fig. 3 also illustrates the position in which a second clasp is ultimately located by proceeding through movements similar to those just described, so that both inner flaps 16 and 18 are positively held in intimate contact over considerable areas with each of the overlapping portions of the outer flaps 12 and 14. After the glue has had sufficient time 30 to dry each of the clasps is readily removed by sliding toward the center of the carton and withdrawing the tongue in a manner the reverse of its insertion.

It will thus be seen that there is provided a 40 novel clasp adapted for use in conjunction with cartons of the type described, which facilitates and assures proper gluing of such cartons. When such clasps are employed the cartons are found to have increased strength resulting from the 45 properly glued surfaces and that such cartons are able to better protect their contents.

While the clasp has been shown as constructed from a stiff resilient wire bent to the shape illustrated, it will be appreciated that the clasp may 50 be constructed of other materials such as a molded or bent plastic or cast metal, the features of the invention, however, being a clasp provided with a tongue adapted to reach within a carton to engage the inner flap and subsequently to 55 operate in conjunction with its bearing points, on the outer flap so as to securely hold the overlapping flaps of the carton in intimate contact over a considerable proportion of their overlapping areas.

60 Although this invention has been illustrated and described in connection with a single varying modification, it is to be understood that the invention is not limited thereto but may be embodied in various modified forms. Since many 65 changes in the construction and arrangement may be made without departing from the spirit of the invention, as will be apparent to those skilled in the art, reference will be had to the appended claims for a definition of the limits of 70 the invention.

What is claimed is:

1. A clasp for temporarily holding the closure flaps of a fibreboard carton in overlapped intimate contact during the gluing thereof, comprising a continuous length of wire bent to form

a tongue portion and a bearing portion extending substantially transverse to said tongue portion adjacent to the center of a central straight section of said tongue portion, and means lying outside of the general plane defined by the straight section of said tongue and said bearing portion for resiliently securing said bearing portion to said tongue portion from one end thereof.

2. A clasp for temporarily holding the closure flaps of a fibreboard carton in overlapped intimate contact during the gluing thereof, comprising a continuous length of wire bent to form a tongue portion and a bearing portion extending substantially transverse to said tongue portion adjacent to the center of a central straight section of said tongue portion and means for resiliently securing said bearing portion to said tongue portion from one end thereof, said bearing portion being slightly spaced from said tongue portion at the section of the bearing portion adjacent to said central tongue portion and being bowed to provide bearing points on opposite sides of said tongue portion spaced at distances from said tongue portion, said means lying outside of the plane generally defined by the straight section and said bearing points.

3. A clasp for temporarily holding the closure flaps of a fibreboard carton in overlapped intimate contact during the gluing thereof, comprising a continuous length of wire bent to form a tongue portion and a bearing portion extending substantially transverse to said tongue portion adjacent to the center of a central straight section of said tongue portion and means for resiliently securing said bearing portion to said tongue portion from one end thereof, said bearing portion being bowed to provide bearing points on opposite sides of said tongue portion spaced at distances from said tongue portion, and said means lying outside of the plane generally defined by the straight section and said bearing points, whereby the area defined between the bearing portion and the tongue portion may unobstructedly receive the closure flaps of a fibreboard carton.

4. A clasp for temporarily holding the inner and outer closure flaps of a fibreboard carton in overlapped intimate contact during the gluing thereof, comprising a slender tongue member adapted for insertion between the adjacent substantially abutting edges of opposing outer flaps, and a bearing member arranged substantially transverse to said tongue member and adjacent to a central portion thereof, and means for securing said transverse member to one end of said tongue member, said tongue member being substantially straight over the portion thereof adjacent to said transverse bearing member, and said means lying wholly outside of the plane defined by the straight portion and the transverse bearing portion.

5. A clasp for temporarily holding the inner

and outer closure flaps of a fibreboard carton in overlapped intimate contact during the gluing thereof, comprising a slender tongue member adapted for insertion between the adjacent substantially abutting edges of opposite outer flaps, and a bearing member arranged substantially transverse to said tongue member and adjacent to a central portion thereof, and means for securing said transverse member to one end of said tongue member without intersecting the plane lying between said bearing member and tongue member and a handle secured to said clasp and extending upwardly from the bearing member side of said clasp.

6. A clasp for temporarily holding the inner and outer closure flaps of a carton in overlapped intimate contact during the gluing thereof, comprising a slender tongue member substantially straight over its major portion adapted for insertion within the carton between the adjacent substantially abutting edges of opposing outer flaps, and a bearing member, transverse to said tongue member at a point substantially central with respect to said tongue member, and means for securing said bearing member and tongue member in closely spaced relation without intersecting the plane lying between said tongue member and said bearing member, whereby said tongue member may be slid underneath an inner flap of a carton and said bearing member slid over the opposing outer flaps, to secure the flaps in contact with one another.

7. A clasp for temporarily holding the closure flaps of a carton in overlapped contact during gluing thereof comprising a length of wire, one end of which is formed into a substantially straight tongue having a slanting short end portion having a rounded extremity, the other end of which is bent to form three portions, a portion transversely arranged with respect to said tongue, a portion resiliently joining the other end of said tongue with one end of the transverse portion without intersecting the plane between said tongue and transverse portion and a handle extending from the other end of said transverse portion.

8. A clasp for temporarily holding the closure flaps of a fibreboard carton in overlapped contact during gluing thereof comprising a length 50 of resilient material, one end of which is formed into a substantially straight tongue having a short slanting end portion, the other end of which is bent or shaped to form three portions, a portion transversely arranged with respect to said tongue, a portion resiliently joining the other end of said tongue with one end of said transverse portion without intersecting the plane generally defined by the straight tongue portion and transverse portion, and a portion forming a handle extending from the other end of the said transverse portion.
